Wesley Clear
ATTORNEY

UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed December 2, 1922. Serial No. 604,508.

To all whom it may concern:

Be it known that I, ORA A. COLBY, a citizen of the United States, and a resident of Irwin, in the county of Westmoreland and State of Pennsylvania, have invented a new and useful Improvement in Electric Furnaces, of which the following is a specification.

My invention relates to electric furnaces and particularly to electric resistance furnaces.

The object of my invention is to provide a heating element of relatively simple, rugged, and inexpensive construction for an electric resistance furnace.

In practicing my invention, I provide a plurality of refractory walls enclosing a furnace chamber, the inner surface of certain of said walls having a plurality of spaced depressions therein. Refractory cleats located in the depressions have a laterally grooved, flat surface projecting from the wall, and flat refractory plates operatively engaging the projecting surface of the cleats constituting a muffle for the furnace chamber. A resistor member comprising a relatively heavy rod or bar extends through the grooves in the cleats and therebetween to be supported thereby.

In the single sheet of drawings.

Figure 1 is a view, in vertical lateral section, of an electric resistance furnace embodying my invention.

Fig. 2 is a view, in front elevation, of one of the walls thereof.

Fig. 3 is a view, in vertical section, of the walls shown in Fig. 2, taken on the line III—III thereof.

Fig. 4 is a view, in vertical longitudinal section, of a refractory cleat, and

Fig. 5 is a view, in front elevation, of a resistor member located in the refractory cleats.

A furnace structure 11 comprises an outer metallic casing 12 having a plurality of supporting members 13 suitably secured thereto. An outer lining 14 comprises a plurality of bricks or blocks of a suitable refractory heat-insulating material. An inner lining 15 comprises a plurality of bricks or blocks of a suitable refractory high-temperature-resisting material, the bricks or blocks com-

prising the two linings being so disposed as to provide a furnace chamber 16, of any suitable or desired contour and dimensions.

The side walls of the furnace and the floor are provided with a plurality of spaced depressions 17, illustrated more particularly in Figs. 2 and 3 of the drawing. In each of these depressions is located a refractory supporting member or cleat 18. One of the members 18 may be of the same length as the depression 17 or it may be shorter, and several of the members 18 may be employed in end-to-end relation in each of the depressions 17. The depth of the members 18 is such that a portion thereof projects into the furnace chamber 16, which portion is provided with a plurality of laterally extending, open grooves 19.

A resistor member 21, comprising a plurality of substantially parallel-extending, straight convolutions of a preformed relatively heavy rod or bar of a suitable resistor material, such as nichrome, has portions of the individual convolutions located in the grooves 19 and extends therebetween and therebeyond substantially as illustrated in Fig. 5 of the drawing. The distance between the spaced depressions 17 and therebefore the distance between the supporting cleats 19, may be made in accordance with the area of cross-section of the resistor member 21, which must be such as to permit of the resistor member being substantially self-sustaining between the spaced supporting cleats.

A plurality of flat plates 22, of a suitable refractory high-temperature-resisting material is located in the furnace chamber 16 adjacent to and operatively engaging the outer grooved surfaces of the supporting cleats 18. Any suitable or desired means for holding the muffle plates 22 in their proper operative positions in the furnace chamber may be employed, and I have illustrated the plates as being provided with interlocking edges, although any other desired method may be employed.

When it is necessary to replace one of the resistor members 21, the muffle plates 22 are removed from the furnace, after which the damaged resistor 21 or one of the cleats 18, may be removed, and be replaced by new

parts after which the muffle plates are again moved into their proper operative positions in the furnace longitudinally thereof.

I have not illustrated a terminal construction or terminal members for the resistor 21, as any suitable or desired construction may be employed.

Various modifications and changes in detail and arrangement may be made without departing from the spirit and scope of the invention, and such modifications are intended to be covered by the appended claims.

I claim as my invention:

1. In an electric furnace, in combination, a plurality of refractory walls enclosing a furnace chamber and having a plurality of spaced recesses therein, cleats in said recesses having a surface extending into said chamber provided with a plurality of laterally extending grooves therein and a resistor member extending through said grooves and between said cleats.

2. In an electric furnace, in combination, a plurality of refractory walls enclosing a furnace chamber and having a plurality of spaced recesses therein, cleats in said recesses having a surface extending into said chamber provided with a plurality of laterally extending grooves therein, a resistor member extending through said grooves and between said cleats, and a muffle plate in said chamber operatively engaging the outer grooved surface of said cleats.

3. In an electric furnace, in combination, a refractory wall constituting a part of an enclosure for a furnace chamber and having a plurality of spaced recesses therein, refractory cleats fitting into said recesses and having a portion extending into said chamber provided with a plurality of laterally extending spaced grooves therein and a resistor member supported by said cleats adjacent said furnace wall.

4. In an electric furnace, in combination, a refractory wall constituting a part of an enclosure for a furnace chamber and having a plurality of spaced recesses therein, refractory cleats fitting into said recesses and having a portion extending into said chamber

provided with a plurality of laterally extending spaced grooves therein and a resistor member comprising a relatively heavy and preformed rod of a refractory resistor material extending through the grooves in said cleats and being substantially self-supporting therebetween.

5. In an electric furnace, in combination, a refractory wall constituting a part of an enclosure for a furnace chamber and having a plurality of spaced recesses therein, refractory members fitting into said recesses and supported by said wall and a relatively heavy and preformed resistor member extending through and between said refractory members and supported thereby adjacent the inner surface of said refractory wall.

6. In an electric furnace, in combination, a refractory wall constituting a part of an enclosure for a furnace chamber and having a plurality of spaced recesses therein, refractory members fitting into said recesses and supported by said wall, a relatively heavy and preformed resistor member extending through and between said refractory members and supported thereby adjacent the inner surface of said refractory wall and a relatively thin flat refractory muffle plate operatively engaging the inner surfaces of said refractory member.

7. In an electric furnace, in combination, a refractory wall constituting a part of an enclosure for a furnace chamber and having a plurality of spaced recesses therein, refractory resistor-supporting members fitting into said recesses and supported by said wall, and having a grooved surface extending beyond the inner surface of said refractory wall, and a relatively heavy and preformed resistor member extending through the grooves in said resistor-supporting members and therebetween and therebeyond closely adjacent to the inner surface of the refractory wall.

In testimony whereof, I have hereunto subscribed my name this 27th day of November, 1922.

ORA A. COLBY.
